HEADBOARD OR THE LIKE

Melbourne F. Smith, Jr., Lenoir, N.C., assignor to Broyhill Furniture Factories, Lenoir, N.C., a partnership

Filed Apr. 15, 1963, Ser. No. 74,418

Term of patent 14 years

(Cl. D5—4)

The back of the headboard or the like is conventionally plain.

The dominant features of my new design reside in those portions shown in full solid lines on the drawing.

I claim:

The ornamental design for a headboard or the like, substantially as shown and described.
